UNITED STATES PATENT OFFICE.

OLIVER C. ECKEL, OF MOUNT VERNON, NEW YORK.

DESIGN FOR A LENS FOR HEADLIGHTS.

60,449.

Specification for Design.

Patented Feb. 21, 1922.

Application filed May 4, 1921. Serial No. 466,756. Term of patent 3½ years.

To all whom it may concern:

Be it known that I, OLIVER C. ECKEL, a citizen of the United States, residing at Mount Vernon, in the county of Westchester and State of New York, have invented a new, original, and ornamental Design for a Lens for Headlights, of which the following is a specification, reference being had to the

accompanying drawing, forming part thereof.

The figure is an elevation of a lens for headlights, showing my new design.

I claim:

The ornamental design for a lens for headlights, as shown.

OLIVER C. ECKEL.
